J. A. BELLMAN

WORKING BARREL

Filed June 4, 1923

Patented June 17, 1924.

1,498,010

UNITED STATES PATENT OFFICE.

JOHN A. BELLMAN, OF HENRYETTA, OKLAHOMA.

WORKING BARREL.

Application filed June 4, 1923. Serial No. 643,313.

To all whom it may concern:

Be it known that I, JOHN A. BELLMAN, a citizen of the United States, residing at Henryetta, in the county of Okmulgee and State of Oklahoma, have invented certain new and useful Improvements in Working Barrels, of which the following is a specification.

This invention relates to working barrels for oil pumps, and more particularly to means for draining the working barrel and tubing to permit oil in the tubing to return to the well when the plunger is removed. In the present invention, I provide a barrel provided with suitable packing members surrounding the plunger and a draining member arranged between the packing and having radial ports or passages communicating with perforations in the barrel where- 20 by any oil or other fluid in the barrel and tubing above it will return to the well when the plunger is removed. Ordinarily, when an oil pump is in use, the tubing becomes filled with oil and the lower standing valve 25 is closed when the plunger is in a state of rest. If the pump is to be removed from the well, the oil in the tubing is lost as the tubing is removed.

In the accompanying drawings, I have shown one embodiment of the invention. In this showing:

Figure 1 is a central vertical sectional view of a portion of an oil pump showing the working barrel and plunger,

Figure 2 is a transverse sectional view on line 2—2 of Figure 1,

Figure 3 is a similar view on line 3—3 of Figure 1,

Figure 4 is a similar view on line 4—4 of Figure 1, and,

Figure 5 is a perspective view of the draining member forming the subject matter of the present invention.

Referring to the drawings, the reference numeral 1 designates a section of ordinary well tubing which is threaded at its lower end to receive a casting 2. This casting is threaded at its lower end to receive a tubing 3 of larger diameter than the well tubing and which forms the working barrel. The lower end of the barrel is internally threaded to receive a casting 4, which is in turn internally threaded on its lower end to receive a section of tubing 5. This 55 section of tubing forms the lower standing valve casing and is provided with

a valve seat 6, adapted to receive a ball valve 7. A plunger 8 is arranged within the barrel and extends into the valve casing. The upper end of the plunger is provided with openings 9 to permit passage of oil into the well tubing. Beneath these openings, there is provided a valve seat 10 adapted to receive an upper standing valve 11. The upper end of the plunger is threaded, as at 12, and is adapted to be connected to a suitable pump rod extending through the casing to the top of the well. Within the working barrel, there is provided cylindrical packing members 13, each of which are provided with a central opening for the passage of the plunger. The working barrel is provided with a plurality of perforations 14, at a point intermediate the top and bottom and arranged adjacent these perforations between the packing members, there is provided a draining member 15. As shown, the draining member is provided with a plurality of radial ports 16, communicating with the central passage of the pump and is further provided with a peripheral groove 17 through which the oil is adapted to pass to the perforations 14 and thus return to the well.

The operation of the device will be apparent. When the plunger is withdrawn from the well and the casing and working barrel to be removed, the well casing is normally filled with oil, most of which is lost as the sections of the casing are removed at the top of the well. By means of the draining apparatus forming the subject matter of the present invention, the oil in the well casing is immediately drained into the well when the plunger is removed.

It is to be understood that the form of my invention herewith shown and described is to be taken as a preferred example of the same, and that various changes in the shape, size, and arrangement of parts may be resorted to without departing from the spirit of the invention or the scope of the subjoined claims.

I claim:

1. In an oil pump, a working barrel, a plunger arranged in said barrel, packing arranged between said plunger and said barrel, and a draining member arranged in said packing to permit oil to be drained from said barrel when said plunger is removed, said barrel being provided with perforations adjacent said draining member.

2. In an oil pump, a working barrel, a plunger arranged in said barrel, packing arranged in said barrel exteriorly of said plunger, the outer wall of said barrel being provided with a plurality of perforations, and means for draining oil through said packing and said perforations when the plunger is removed.

3. In an oil pump, a working barrel, a plunger arranged in said barrel, a plurality of cylindrical packing members arranged in said barrel and surrounding said plunger, and a draining member arranged between a pair of said packing members, said barrel being provided with perforations adjacent said draining member.

4. In an oil pump, a working barrel having perforations formed therein intermediate its ends, a plunger mounted in said barrel, a plurality of packing members arranged in said barrel and surrounding said plunger, and a draining member interposed

between a pair of packing members adjacent said perforations, said draining member being provided with a plurality of radial passages.

5. In an oil pump, a working barrel having perforations formed therein intermediate its ends, a plunger mounted in said barrel, a plurality of packing members arranged in said barrel and surrounding said plunger, and a draining member interposed between a pair of packing members adjacent said perforations, said draining member being provided with a plurality of radial passages, and being further provided with a circumferential groove communicating with said passages.

In testimony whereof, I affix my signature in presence of two witnesses.

JOHN A. BELLMAN.
